UNITED STATES PATENT OFFICE.

JAMES HOWDEN, OF GLASGOW, COUNTY OF LANARK, SCOTLAND.

AIR-SUPPLYING DEVICE FOR STEAM-BOILER FURNACES.

SPECIFICATION forming part of Letters Patent No. 288,437, dated November 13, 1883.

Application filed September 13, 1883. (No model.) Patented in England June 14, 1882, No. 2,789; in France December 12, 1882, No. 152,584, and in Belgium December 19, 1882, No. 59,911.

To all whom it may concern:

Be it known that I, JAMES HOWDEN, a subject of the Queen of Great Britain and Ireland, and residing at Glasgow, in the county 5 of Lanark, Scotland, have invented certain Improved Air-Supplying Devices for Steam-Boiler Furnaces, (for which I have obtained the following patents: in Great Britain June 14, 1882, No. 2,789; in France December 12, 1882, No. 152,584; in Belgium December 19, 1882, No. 59,911,) of which the following is a specification.

My invention has principally for its object the supplying of air required for combustion 15 in the furnaces of marine and other steam-boilers in a novel and improved manner, by which a more rapid and effective combustion may be obtained and the great waste of heat may be diminished, which ordinarily takes 20 place in existing arrangements, while my improvements, as applied in connection with marine boilers, have the important advantage of securing ventilation and coolness in the stoke-holds.

25 In carrying out my invention an important feature is the use, in combination with other devices, of a forced draft to give a more rapid and effective combustion of the coal or other fuel used in the furnaces. The air for combustion is supplied at a pressure above 30 that of the atmosphere, as is done in torpedo-boats; but instead of inclosing the entire stoke-hold and keeping it air-tight under pressure, which is quite impracticable in large vessels, 35 or even in vessels of moderate size used for ordinary purposes, the air is confined in an air-tight casing formed by a false front of thin plates inclosing a space or spaces in front of the furnaces, and at other parts of the boilers 40 where considered necessary or desirable in carrying out my invention with the object of saving heat. In some cases the air in the casing may have access to the furnaces or ash-pits just like the air from the stoke-hold in existing arrangements; but in arrangements 45 which I prefer there is in each case a common air-chest or compartment of the casing which is separated by partitions from the furnaces and other parts, while the furnaces are separated from each other, and the supply of air to each is regulated by means of suitable

valves. One compartment may be used for admitting air above the fuel of each furnace; also, through tubular fire-bars and into the ash-pit thereof, one valve being used to regulate the admission and for shutting off the supply when fuel has to be introduced or ashes withdrawn, the quantities of air admitted to these several parts being regulated by gratings or valves on the interior doors. I, however, prefer to admit the air separately, either above or below the fuel or through the fire-bars, separate partitions and valves being provided for this purpose. The fire-gases, after passing through or over the heating-surface of the boiler or boilers, may be prevented from passing away too rapidly, which the pressure employed would tend to make them do, by partially closing the ends of the tubes of tubular boilers or analogous parts of other 50 boilers, or the velocity of the escaping gases may be regulated at some part of the passages leading to the chimney or funnel, and the gases may be made to give up a considerable portion of their remaining heat to the air supplied 55 to the common air-casing by being passed through tubular or other suitable passages in a part of the air-casing or in a casing communicating therewith, the cold air entering from the fan or other blowing apparatus being made to 60 pass in contact with the outsides of such tubular or other passages. By this means the great heat which would otherwise be lost, as in torpedo-boats, or in ordinary steam-boilers, is utilized in heating the air for combustion, thus 65 effecting a great economy of fuel and obtaining from a much smaller boiler or fire-grate an evaporation of water or supply of steam equal to that from the usual marine-boiler worked with natural draft, while at the same 70 time the boiler-room or stoke-hold is kept cool and the temperature of the uptakes and funnel is comparatively low. As I prefer to work 75 the fan or blowing apparatus in the stoke-hold, the air therein is always kept cool and fresh 80 by the supply which continually enters to replenish what is taken by the fan; and as the false front of the air-casing which covers the greater part of the boiler ends is always comparatively cool, no heat from the furnaces or 85 ash-pits is radiated into the stoke-hold, as in ordinarily-fired boilers, or as in torpedo-boats, 90 95 100

so that with the shell of the boilers properly protected by a non-conducting material no part of the boiler-room can be heated to any great extent from the working of the boilers.

5 In the accompanying drawings, Figure 1 is a front elevation of a marine boiler with one-half shown in vertical section; and Fig. 2 is a vertical section, as at right angles to Fig. 1.

The fan or blowing apparatus employed in 10 carrying out my invention may be of any suitable known kind, but is not shown in the drawings. The air from the blowing apparatus enters by a pipe, 3, into a space between the front of the boiler itself and an outer shell 15 or casing constructed of thin plating. This space is divided by various plates or partitions, there being an upper horizontal partition, 4, extending completely across the front, and above which is a compartment or space, 20, 5, communicating directly with the uptake 6. Smoke-box compartments 7 are formed in front of the tubes, and these compartments communicate with the top space, 5, through vertical tubes 8. A horizontal plate, 9, closes 25 the space between the two smoke-box compartments 7 and another horizontal plate, 10, indicated by dotted lines, closes the top of the space between the outer side of that smoke-box compartment which is nearest the air-in- 30 let 3 and the side of the casing, so that the air entering by the pipe 3 has first to proceed horizontally across the front of the boiler and to pass in contact with the tubes 8, from which it will take up some heat.

35 The two smoke-box compartments 7 have doors fitted to them to give access for cleaning the tubes, and one, 11, of these doors is shown at the left-hand side of Fig. 1, but is not seen in the sectional half of the figure. 40 After passing horizontally across the front of the boiler, as described, the air, partly warmed by the vertical tubes 8, descends through the space 12, which is between the right-hand smoke-box compartment 7 and the outer side 45 of the air-casing, and spreads over the part of the front of the boiler which is below the smoke-box compartments 7.

A circular casing, 13, is fixed in front of each furnace 14, and also incloses a space in 50 front of the ash-pit 15, and this circular casing 13 is formed with two horizontal partitions, forming three compartments or spaces, 16 17 18, within the circular casing. The outer front shell of the air-casing, which covers the larger 55 part of the front of the boiler, practically extends over the casing 13, but is formed with a hinged flap or door, 19, to give access to the ash-pit 15, and is also fitted with a fire-door, 20. This fire-door 20 has fixed to it by studs 60 an inner door or plate, 21, for closing the opening from the air-space into the furnace 14.

The opening for the outer fire-door, 20, is made larger than that for the inner door, 21, so that the inner door may easily open outward along with the outer door, and the inner door is 65 formed with perforations to admit air, and with inclined plates on its inner side to deflect the entering air downward on the fuel.

The perforations in the inner fire-door, 21, to a certain extent control the quantity of air 70 entering above the grate-bars; but in addition I prefer to use an adjustable valve, 22, for regulating the proportion of air which passes from the main space of the air-casing into the compartment 16, in which the fire-doors 20 21 75 are situated.

The air which enters the middle compartment, 17, and which can be regulated by means of valves 23, has access from that compartment either into tubular fire-bars communicating 80 with orifices in the bridge or into hollow bars 24, of which there is one extending along each side of each furnace 14. These hollow side bars are a little higher than the grate-bars, and are perforated for the issue of the air from 85 them into the furnace. The lower air-compartment, 18, which communicates with the ash-pit 15, is also provided with valves 25 for regulating the proportion of air entering that 90 way.

With these arrangements the air may be distributed to the different parts of the furnace in the respective proportions which may be found to give the best results.

What I claim as my invention of air-supply- 95 ing devices for steam-boilers is—

1. In combination, a fan or blower, an air casing or space through which the air is forced, such space having tubes for the waste fire-gases to pass through, and partitions in 100 the air-casing forming in front of each furnace and ash-pit compartments fitted with valves for the separate regulation of air passing therethrough into the furnace above the grate-bars into hollow bars and into the ash- 105 pit, the various parts being arranged and operating substantially as and for the purposes herein set forth.

2. In combination, a fan or blower to supply air under pressure, and an air-casing formed 110 upon the front of a steam-boiler to prevent overheating of the stoke-hold and to utilize the heat radiated from the front of the boiler in heating the air-supply, substantially as herein set forth.

In testimony whereof I have signed my name to this specification in the presence of two subscribing witnesses.

JAMES HOWDEN.
